UNITED STATES PATENT OFFICE

DENNIS PARKS, OF ST. LOUIS, MISSOURI

LEATHER-GRADING MACHINE

Application filed October 16, 1929. Serial No. 399,886.

This invention relates to a machine for grading leather, and has for its general object improvements in the leather grading machine forming the subject matter of my pending application, Serial No. 375,642, filed July 3rd, 1929.

In the machine of the application referred to, I disclose the use of endless carriers in the form of coiled wire cables arranged to move in parallel relation from end to end of the machine, and which were intended to provide a secure grip on the pieces of leather to be graded while permitting the ready removal of such pieces from between the wire cables by the grading rollers. While the machine involving the above feature operates, in the main, satisfactorily, nevertheless it was found in practice that very often, and especially when a relatively thick piece of leather was about to be discharged by the grading rollers, the wire cables or carriers would be twisted or turned axially as the piece of leather was pulled from between them, with the result that a following piece of leather, which had not yet been carried to the position between the rollers where it would be discharged, would be thrown out by the partial rotation of the carriers, and thus improper grading would result.

In overcoming this disadvantage of my prior machine, I dispense with the coiled wire cables and substitute therefor an endless chain, the bottom edges of the links of which are adapted to engage and move the pieces of leather to be graded between the grading rollers, this chain or carrier co-operating with a stationary bar, the upper surface of which is corrugated, the pieces of leather being adapted to be gripped between the chain and the bar and to be moved over the bar by the chain until the proper grading position of the pieces of leather, in turn, is reached when the grading rollers operate, as in the case of my previous machine, to pull the piece of leather from between the chain and the bar and to discharge it into an appropriate receptacle.

The present invention is also characterized by novel means for causing a yielding engagement of the gripping chain or carrier

with the pieces of leather, and by other novel features of construction which will be more clearly understood from the detailed description to follow taken in connection with the accompanying drawings, in which—

Figure 1 is a plan view of a machine constructed according to my invention;

Figure 2 is a view in front elevation thereof, a portion of the machine being broken away to better illustrate the construction;

Figure 3 is a section on an enlarged scale taken on the line 3—3 of Fig. 2 viewed in the direction of the arrows;

Figure 4 is a sectional view on an enlarged scale taken on the line 4—4 of Fig. 3 and viewed in the direction of the arrows;

Figure 5 is an enlarged cross-sectional view showing the stationary gripping bar and a portion of one of the links of the gripping chain co-operating therewith, the section being taken on the line 5—5 of Fig. 4;

Figure 6 is a sectional view taken on the line 6—6 of Fig. 4 illustrating the manner of mounting the rollers in the pressure members which co-operate with the gripping chain to produce a yielding contact on the pieces of leather.

Referring now to the drawings, the numerals 1, 2 indicate standards which are substantially A-shaped in form and located, respectively, at opposite ends of the machine, said standards supporting the operating parts of the machine. Mounted on the upper ends of these standards is a container 3 for holding the lifts or other pieces of leather to be graded, said container extending beyond the standard 1 at the left of the machine (as shown in Figs. 1 and 2) and projecting forwardly at such extended portion, as indicated at 4 in Fig. 1, the front end of this projecting portion being open and the projection itself providing a table on which the pieces of leather rest in convenient position to be picked up by the operator and fed into the machine. Mounted in bearings 5, 6 provided at each end of the machine are two cylindrical grading rollers 7, 8, the upper grading roller 7 being mounted in the bearings 5 and the lower grading roller 8, in the bearings 6. The bearings of these rollers are

so disposed that at the front end of the machine, that at the left of Figs. 1 and 2, the rollers are separated by a distance approximately one-fourth of an inch, while at the rear end of the machine they are separated by a space of approximately one-sixteenth of an inch. The length of the rollers and the gradual narrowing of the space between them from the front to the rear end of the machine are so proportioned as to enable me to provide for conveniently grading nine different thicknesses of leather corresponding in thickness to the well known "irons" used for grading leather of numbers running from No. 10 to No. 2. Such numbers are preferably placed on the front of the machine above the grading rollers, as indicated by the letter A, to disclose the various points along the grading rollers at which pieces of leather corresponding in thickness to the "iron" of the number positioned at the zone of discharge. There is a space between each of the numbers of several inches and a piece of leather corresponding in grade with any given number will be discharged at some point between that number and the preceding one. If a more accurate degree of grading is required, it can be obtained by increasing the number of receptacles, hereinafter referred to, for receiving the pieces of leather ejected by the grading rollers. At its rear end, the grading roller 7 is provided with a stub shaft 9 on which is mounted a drive pulley 10 adapted to receive a belt (not shown) driven from any suitable source of power. Mounted on the shaft 9 is a gear 11 which meshes with a similar gear 12 provided on the end of the grading roller 8, whereby the grading rollers may be rotated in unison and at the same rate of speed from the shaft 9. In order to carry the pieces of leather to be graded between the rollers 7 and 8, I provide the following mechanism:

Mounted at the top of the standards 1 and 2 at the front of the machine and extending from end to end thereof is an angle bar 13 (Figs. 3 and 4). Secured on the front face of this angle bar is a filler strip 13a which is shaped to provide a series of separated recesses 14 (Fig. 4) in each of which is mounted a pressure member or block 15. Each of these blocks is provided at opposite ends, respectively, and in its outer face, with recesses 16 from the bottom center of which project short shafts 17 on each of which is rotatably mounted an anti-friction roller 18. Centrally of its length each of the pressure blocks 15 is provided with a circular recess 19 which houses a coil spring 20 the upper end of which bears against the underside 21 of the filler strip 13a forming the top of the corresponding recess 14. These pressure blocks are floating blocks; that is to say, either end may raise while pivoting on the other end, and to any degree, the coil spring

20 exerting pressure on the block at all times and in all positions thereof. The pressure blocks are loosely confined in the recesses 14 preferably by means of a series of thin metal plates 21a which are secured on the front side of the filler strips 13a by means of screws 21b, these screws, as shown in Fig. 4, passing through projections on the filler strip and serving to secure the latter to the front face of the angle bar 13.

Mounted in suitable bearings at each end of the machine is a substantially vertically disposed shaft 22 on which is secured a sprocket wheel 23, and around these sprocket wheels passes an endless chain 24 (Figs. 2, 3 and 4). In the drawings, I have only shown one of the sprocket wheels 23, but that at the other, or right-hand, end of the machine is mounted in exactly the same way as shown at the left-hand side of the machine in Fig. 2. Positioned beneath the chain 24 and extending parallel therewith is a bar 25 (Figs. 3, 4 and 5) which is secured to the front face of the angle bar 13 by means of screws 26. The upper surface or edge of the bar 25 is corrugated, as indicated at 27 in Fig. 5. The links 28 of sprocket chain 24 are vertically disposed and each of said links at one end in its lower edge is provided with a shoulder 29 (Fig. 5) which shoulders are for the purpose of engaging the pieces of leather and moving them over the upper surface of bar 25. One of the grooves, preferably the outer groove, on the upper surface of bar 27 is adapted to receive the lower edges of links 28 and guide the links in their passage over the bar. The gripping chain 24 may extend directly from one sprocket wheel 23 to the other, but preferably, as shown in Figs. 1 and 3, I cause the rear run of this chain to pass over a tightener sprocket 30 (shown by dotted lines in Fig. 1) mounted on an arm 31 which is pivotally mounted intermediate its ends at 32 on a bracket 33 supported from the underside of the container 3 and a coil spring 34, connected at one end to the inner end of said arm and at its other to the angle bar 13, normally forces the tightener sprocket 30 outward to maintain the proper tension on the gripping chain 24. It is desirable to maintain the upper edge of the links 28 lubricated to minimize friction between the links and the rollers 18, and to this end, I mount on the hub of the tightener sprocket 30 a relatively thick circular washer of felt 35 (Fig. 3) which is maintained supplied with lubricant and continuously bears against the upper edge of the chain 24 in the movement of the latter. Extending from end to end of the machine is a drive shaft 36 mounted at each end in bearings 37 and provided at one end with a pulley 38. The stub shaft 9 previously referred to is provided with a drive pulley 39 and a belt 40

passes over pulleys 38 and 39 whereby shaft 36 is driven from stub shaft 9 when the latter is rotated by pulley 10. Mounted at the shaft 36 at each end thereof is a bevel gear 41 which meshes with a bevel gear 42 provided at the lower end of the respective shafts 22 (Fig. 2). When the shaft 36 is rotated the sprockets 23 will be driven to move the gripping chain 24 in a direction from left to right of the machine, as shown in Figs. 1 and 2.

In order to reduce the friction which would result if the rollers 18 (Fig. 4) were adapted to engage the upper edges of the links of the chain 24, I provide for maintaining the pressure blocks 15 in a position slightly elevated above the upper edge of said chain. To this end, I secure on the front face of the angle bar 13 to extend the length of said angle bar a metal strip 43 (Fig. 3) and located between said angle bar and the gripping bar 25, the latter and the strip 43 being secured to the angle bar by the screws 26, previously referred to. The pressure blocks 15 are adapted to ride on the upper edge of the metal strip 43 and thus maintain the rollers 18 out of contact with the upper edge of chain 24, as clearly shown in Fig. 4.

30 In order to facilitate the entrance of the pieces of leather between the bar 25 and the gripping chain 24, I preferably locate a gripping or friction roller 44 (Fig. 2) beneath the lower edge of chain 24 at about the point 35 of widest separation thereof from the upper edge of the bar 25, or just beyond the end of said bar, as shown in Fig. 2, which roller facilitates the movement of the leather into the gripping position between the chain and gripping bar. In other words, it was found that where the leather was inserted directly between the chain 24 and bar 25 there was a 40 tendency on the part of the pieces of leather to lag momentarily owing to the resistance offered to its movement by the stationary bar 25. By placing the roller 44 at the point 45 where the pieces of leather are fed into the machine, this cause of resistance to movement is overcome and, although the engagement 50 of the chain with the pieces of leather is very slight at this particular point, the said pieces will readily move into position to be tightly gripped between the chain and the bar 25.

55 The corrugations 27 in the upper edge of bar 25 serve, by engaging the underside of the pieces of leather, to guide them in a right line in their passage between the grading rollers 7 and 8 and prevent any tendency of 60 the pieces of leather being moved from between the chain and bar until they have reached, in turn, the respective zones on the grading rollers where the frictional engagement of the latter with the pieces of leather 65 will cause their discharge.

A desired number of containers may be positioned side by side to extend lengthwise of the machine under the grading rollers 7 and 8 to receive the pieces of leather thrown out at various points along the length of said rollers. These are usually in the form of bags 45 (Figs. 1 and 3) secured on hooks 46 (Fig. 3) and provided at the outer and inner ends, respectively, of arms 47 which are secured on the underside of the angle bar 13 70 and project outwardly therefrom.

In operation, the container 3 being supplied with the pieces of leather to be graded, the operator takes up pieces of leather from the table 4 and inserts them in succession between the gripping chain 24 and the roller 44 at the front or left-hand end of the machine (Fig. 2). By moving each piece of leather as inserted to the right, it is engaged by the chain and moved into gripping relation between said chain and the upper edge of the gripping bar 25, and continues to be moved thereafter from the front to the rear end of the machine. The insertion of a piece of leather between the chain and the gripping bar necessarily raises the chain at this point out of engagement with the bar, and as this raised portion passes under one or the other of the rollers 18 of a pressure block 15, the corresponding end of the latter will be 95 raised against the resistance of the coil spring 20, and as soon as the raised portion of the chain passes beyond such roller the spring 20 acts to force the roller downward or to normal position. As, in practice, the pieces of 100 leather will be rapidly inserted between the gripping chain 24 and the gripping bar 25, the yielding of the pressure blocks 15, or rollers 18 thereof, is very important, as it permits of the chain 24 maintaining a firm 105 grip on the pieces of leather regardless of the varying thicknesses of the leather. For example, if a piece of leather an eighth of an inch in thickness passes beneath a roller 18 and the next piece of leather is only a sixteenth of an inch thick, the corresponding 110 end of the pressure block and its roller will yield in an upward direction to accommodate the thickness of the first piece, and the chain is immediately moved toward the bar 25 as soon as the thicker piece of leather has passed beneath a roller 18 to enable the chain to grip, or maintain the grip, on the thinner piece of 115 leather following.

From the above statement of the operation, it will be seen that the grading rollers will operate automatically to remove from between the gripping chain and gripping bar, and discharge from the machine at various points throughout their length, pieces of leather which correspond in thickness to the width of the space between the rollers at such points. It will also be seen that the greater the number of containers 45 that are employed, the more accurate the grading will be. 120

While I have shown and described the grading rollers as being cylindrical and arranged in converging relation to each other to provide a gradually narrowing space extending throughout the length of the rollers, it will be obvious to those skilled in the art that I could equally well employ the construction of grading rollers shown in the prior patent to Mitchell & Parks, No. 1,163,358, dated December 7th, 1915, in which one of the rollers is provided with a series of separated grading areas, but in which the space, as a whole, between the rollers gradually narrows, as in the present invention.

I claim:

1. A leather grading machine comprising a pair of grading rollers having a space between them gradually narrowing in width from one end of the rollers to the other, and means for successively conveying pieces of leather lengthwise of the rollers with a portion of each piece projecting into the space between the rollers, comprising a stationary gripping member extending parallel to said rollers substantially throughout the length thereof and an endless carrier adapted to move parallel to and in gripping relation with said stationary gripping member.

2. A leather grading machine comprising a pair of grading rollers having a space between them gradually narrowing in width from one end of the rollers to the other, and means for successively conveying pieces of leather lengthwise of the rollers with a portion of each piece projecting into the space between the rollers, comprising a stationary gripping member extending parallel to said rollers substantially throughout the length thereof and having an upper corrugated edge, and an endless carrier adapted to move parallel to and in gripping relation with the corrugated edge of said gripping member.

3. A leather grading machine comprising a pair of grading rollers having a space between them gradually narrowing in width from one end of the rollers to the other, and means for successively conveying pieces of leather lengthwise of the rollers with a portion of each piece projecting into the space between the rollers, comprising a stationary bar extending parallel to said rollers substantially throughout the length thereof and provided with an upper edge having longitudinally extending corrugations and an endless gripping chain having its links vertically disposed with reference to said bar and adapted to be moved thereover with the lower edges of its links normally in guiding engagement with one of the corrugations of said bar.

4. A leather grading machine comprising a pair of grading rollers having a space between them gradually narrowing in width from one end of the rollers to the other, and means for successively conveying pieces of leather lengthwise of the rollers with a por-

tion of each piece projecting into a space between the rollers, comprising a stationary gripping member extending parallel to said rollers substantially throughout the length thereof and an endless sprocket chain adapted to move parallel to and in gripping relation with said stationary gripping member, the links of said chain being provided with shoulders for engaging the pieces of leather to move them over said gripping member.

5. A leather grading machine comprising a pair of grading rollers having a space between them gradually narrowing in width from one end of the rollers to the other, means for successively conveying pieces of leather lengthwise of the rollers with a portion of each piece projecting into the space between the rollers, comprising a stationary gripping member extending parallel to said rollers substantially throughout the length thereof and an endless carrier adapted to move parallel to and in gripping relation with said stationary gripping member, and a gripping roller positioned at the end of said stationary gripping member beneath said carrier to facilitate the feed of the pieces of leather between the carrier and said gripping member.

6. A leather grading machine comprising a pair of grading rollers having a space between them gradually narrowing in width from one end of the rollers to the other, means for successively conveying pieces of leather lengthwise of the rollers with a portion of each piece projecting into the space between the rollers, comprising a stationary gripping member extending parallel to said rollers substantially throughout the length thereof and an endless carrier adapted to move parallel to and in gripping relation with said stationary member, and a series of pressure members yieldingly mounted above said carrier at intervals throughout the operative length thereof to maintain gripping engagement between said carrier and the gripping member on pieces of leather of varying thickness being drawn by the carrier between the grading rollers.

7. A leather grading machine comprising a pair of grading rollers having a space between them gradually narrowing in width from one end of the rollers to the other, means for successively conveying pieces of leather lengthwise of the rollers with a portion of each piece projecting into the space between the rollers, comprising a stationary gripping member extending parallel to said rollers substantially throughout the length thereof and an endless carrier adapted to move parallel to and in gripping relation with said stationary gripping member, and a series of pressure blocks yieldingly mounted above said carrier throughout the operative length thereof and provided at opposite ends with rollers adapted to be raised by the carrier

in the portion thereof engaging a piece of leather, whereby to maintain gripping contact between the carrier and the gripping member on pieces of leather of varying thickness being drawn by the carrier between the grading rollers.

8. A leather grading machine comprising a pair of grading rollers having a space between them gradually narrowing in width from one end of the rollers to the other, means for successively conveying pieces of leather lengthwise of the rollers with a portion of each piece projecting into the space between the rollers, comprising a stationary gripping member extending parallel to said rollers substantially throughout the length thereof and an endless carrier adapted to move parallel to and in gripping relation with said stationary gripping member, a series of floating pressure blocks positioned at intervals throughout the operative length of said carrier immediately above the same, and a spring located centrally of each block for exerting pressure thereon, said blocks being adapted to yield to varying degrees as pieces of leather of different thicknesses are moved by the carrier beneath them, whereby gripping contact between the carrier and the gripping member on such pieces of leather is maintained through the operative length of said carrier.

9. A leather grading machine comprising a pair of grading rollers having a space between them gradually narrowing in width from one end of the rollers to the other, means for successively conveying pieces of leather lengthwise of the rollers with a portion of each piece projecting into the space between the rollers, comprising a stationary gripping member extending parallel to said rollers substantially throughout the length thereof and an endless carrier adapted to move parallel to and in gripping relation with said stationary member, a series of pressure members yieldingly mounted above said carrier at intervals throughout the operative length thereof to maintain gripping engagement between said carrier and the gripping member on pieces of leather of varying thickness being drawn by the carrier between the grading rollers, and means for normally maintaining said pressure members out of contact with said endless carrier.

In testimony whereof, I have hereunto set my hand.

DENNIS PARKS.
